UNITED STATES PATENT OFFICE.

MATHIAS HAGERUP, OF HANLEY, SASKATCHEWAN, CANADA.

BOLTLESS PLOWSHARE.

No. 914,139.

Specification of Letters Patent.

Patented March 2, 1909.

Application filed July 31, 1908. Serial No. 446,321.

To all whom it may concern:

Be it known that I, MATHIAS HAGERUP, farmer, of the village of Hanley, in the Province of Saskatchewan, Canada, have invented certain new and useful Improvements 5 in Boltless Plowshares, of which the following is the specification.

My invention relates to plow shares and the object of the invention is to provide 10 means which will allow of ready adjustment of the share to the plow, doing away with the bolts heretofore employed.

It consists essentially in a share adapted to fit to the mold board and to the landside, 15 releasable clamping means securing the share to the mold board; and means interconnecting it with the land side, the parts being arranged and constructed as hereinafter more particularly described.

20 Figure 1 is an inverted perspective view of the share, the mold board, and land side, showing them attached. Fig. 2 is a perspective view showing the plow with the land side towards the observer. Fig. 3 is 25 an inverted view of the plow, the share being shown in a disconnected position.

In the drawings like numerals of reference indicate corresponding parts in each figure.

30 1 is the land side the forward end of which is brought to the usual point at 2, such end being partially cut away, as at 3, to form a joint for the projecting portion carried by the share, as later described.

35 4 is the mold board which is fastened in the usual manner to the land side and of the usual shape, and 5 is a brace or tie rod passing between the land side and the mold board.

40 6 is a plate firmly fastened to the under face of the mold board and it extends slightly beyond the edge 7 of the mold board in order to form a rest or brace for the upper edge of the share.

45 8 is a forked plate secured also to the mold board immediately to the side of the plate 6, and the forked end of the plate extends beyond the edge 7 of the mold board.

9 is a share having the upper edge 10 50 adapted to engage with the edge 7 of the mold board. The share is provided with a

downwardly extending portion 11 which passes from the point of the share and is adapted to fit against the point of the land side which, as before stated, is cut away to 55 receive it.

12 is a bent pin extending from the rear edge of the portion 11, and 13 is a curved opening formed in the land side adapted to receive the pin.

60 14 is an eye bolt secured to the inner face of the share and placed so that when the share is in position for using it will pass between the forked ends of the plate 8. 15 is a hook secured to the latter plate and designed 65 to engage with the eye when it is received between the forked ends of the plate. It will be understood that the plates 6 and 8 are both curved to fit the continuous curve of the share and the mold board.

70 In placing the share on the plow the pin is inserted within the opening and the share is closed over till it engages with the edge 7 of the mold board. This brings the eye within the forked end of the plate and as soon as the 75 hook is closed with the eye the share is secured to the plow. It will thus be seen that by my invention a most convenient and ready means for attaching the plow share to, and removing it from the plow is provided, 80 owing to its simplicity and rigidity, which amply fulfills the purpose for which it is designed.

75 What I claim as my invention is:

1. In a boltless plow share the combination with the land side and the mold board, the said land side having a forward projecting end piece, of a share having a downwardly directed portion adapted when in closed position to rest against the projecting portion of 90 the land side; a curved pin carried by the downwardly extending portion and adapted to pass into a curved opening provided in the land side; and releasable clamping means for securing the share to the mold board, as and 95 for the purpose specified.

2. In a boltless plow share the combination with the land side and the mold board, the said land side having a forward projecting end piece, of a share having a downwardly 100 directed portion adapted when in closed position to rest against the projecting portion of

the land side; a curved pin carried by the downwardly extending portion and adapted to pass into a curved opening provided in the land side; a forked plate secured to and extending from the under side of the mold board; an eye bolt carried by the share; and a hook secured to the latter plate and adapted to engage with the eye when the eye is re-

ceived between the forked ends of the plate, as and for the purpose specified. 10

Signed at Hanley in the Province of Saskatchewan, this 30th day of June, 1908.

MATHIAS HAGERUP.

In the presence of—

FRED MARTINSON,

BERT DERDALL.
